PROCESS AND MACHINE FOR THE MANUFACTURE OF TUBES MADE OF PAPER OR LIKE MATERIAL

René Jarrier, St.-Quentin, France, assignor to Bartlett Arkell, New York, N. Y.

Application May 1, 1928, Serial No. 274,331
In France June 10, 1927

21 Claims. (Cl. 93—81)

My invention relates to a process for the manufacture of strong tubes of paper or like substance, more particularly of tubes adapted for the manufacture of bags, which may contain a 5 rather considerable weight of material, and in particular of the so called "valve-bag" type. The invention relates also to a machine by which the said process may be carried into effect.

For the purpose of providing rigid containers, 10 it has already been proposed to manufacture paper tubes by winding a band of paper upon itself in several turns, the different layers being made to adhere strongly together by means of a continuous coat of adhesive material spread over 15 the whole surface.

When applied to tubes of large diameter, such a process obviously causes a great waste of adhesive; moreover when strong bags are to be made from said tubes, which requires the use of a thick 20 paper, the uninterrupted coat of adhesive gives to the finished tube a hardness or stiffness whereby the manufacture of a bag is made very difficult; in particular, the manufacture of the so-called "valve-bags" is made quite impossible.

25 One object of my invention is to provide a process of making paper tubes of great capacity and strength whose walls will however have a great suppleness allowing to easily manufacture them into valve bags. Another object is to produce tubes of the aforesaid character which will comprise several convolutions and will be far more resisting than the similar bags heretofore known which are made of a number of several independent sheets pasted together end to end. 30 Another object is to provide a machine of a very simple and inexpensive character for carrying out such a process and which will however operate in an accurate and reliable manner.

With these and other objects in view, my invention consists of certain features as well as of the combination and arrangement of parts hereafter described and more particularly pointed out in the claims.

40 A preferred embodiment of a machine according to my invention is illustrated in the accompanying drawings in which:

Fig. 1 is a general elevational view of the machine, and

Fig. 2 is the corresponding side view.

50 Fig. 3 is a detail view of the winding mandrel, with parts broken away.

Fig. 4 is a detail view of the pivoted bearing.

Fig. 5 is an elevational view of the device for forming the bellows parts, and

55 Fig. 6 is a section on the line 6—6 of Fig. 5.

In the example herein represented, the machine comprises a base plate or table 1 mounted on two cross-braced legs 2. The two supports 3 and 4 which are mounted on the said base plate carry the main shaft 5, by means of the two bearings 6 and 7 whereof one, 6, is pivotally mounted, as will be hereinafter described in detail. Upon the shaft 5 is mounted the mandrel 8 consisting of a sheet 9 of aluminium or other material wound upon the plates 10 secured to the shaft 5. A portion of the sheet 9 forms a shutter 11, one of whose edges is hinged to the stationary part of the mandrel 8 in such manner (for instance) that it will rotate on an axle 12 which is flush with the external surface of the mandrel and is parallel 10 with the shaft 5. The other edge is supported by the eccentric discs 13 secured to a shaft 14 mounted in suitable supports or bearings secured to the end-plates 10. A handle 15 mounted on the end of the shaft 14 serves to rotate the latter 20 and hence to control the said shutter which is thus movable at will in the interior of the mandrel 8. The edge supported upon the disks is bevelled and may fit upon the corresponding edge of the fixed part of the mandrel 8, and these two 25 edges may be faced with india rubber, felt or like flexible substance by which the adhesion will be increased. The greatest distance between the axis of revolution of the eccentric discs 13 and their periphery is greater than the distance between said axis and the inner surface of the 30 mandrel engaged by the periphery of the discs, so that, by turning in one direction the shaft 14 through the handle 15, the discs will act to press the free edge of the shutter upon the corresponding edge of the mandrel whereby the sheet of paper will be firmly clamped to the mandrel, and by rotating the shaft in the opposite direction the shutter will be moved away from the indeformable 35 part of the mandrel, whereby the sheet of paper 40 will be released.

Upon the shaft 5, which extends beyond the support 4, is loosely mounted the driving pulley 16. A slide sleeve 17 which rotates with the shaft 5 serves to connect together the said shaft by 45 means of a coupling of the friction or other type. The sleeve 17 is also secured to a tapered member 18 coacting with a stationary tapered member 19. Due to the friction between these two tapered members, the shaft 5 can be braked and can be 50 instantly stopped. The end of the shaft 5 is mounted in a third bearing 20 which is secured to a support 21 mounted upon the base plate 1. A fork 22 rotatable on an axle 24 mounted on the support 21 is engaged in a groove 23 in the sleeve 55

17; the other end of said fork—urged by the spring 25—carries a roller 26 coacting with the cam 27 keyed to shaft 28 rotatable in the support 21. The said cam carries a boss which makes contact with the roller 26 and thus oscillates the fork 22. By a suitable fastening device 22a—for instance a rod or pin—the fork 22 can be held in the uncoupling position. A chain 29 is disposed upon the chain wheels 30 and 31 mounted respectively on the shafts 5 and 28, so that the shaft 5 can drive the shaft 28. The diameters of the said wheels are such that the ratio of the speeds of rotation will depend upon the number of revolutions to be made by the said tube.

15 If for instance the tube is to comprise four thicknesses of paper, the diameter of the wheel 30 will be $\frac{1}{4}$ the diameter of the wheel 31, so that the shaft 5 will make four revolutions while the shaft 28—and with it the releasing cam 27—makes only one revolution.

10 The two rollers 32—33 are mounted upon the respective shafts 34—35 which are parallel to the shaft 5 and are disposed on either side of the vertical plane passing through the said shaft. 25 The said rollers are guided in the vertical guides 36—37 by the sliding members 38, and are supported only at the ends by means of the rollers 39 resting upon the cams 40. A vessel 41 containing the adhesive paste is disposed below the rollers 32—33 and it is mounted upon the blocks 42 disposed on the supports 43—44 which are secured to the base plate 1 and in which are formed the guides 36—37. The said cams are mounted upon the ends of the shafts 45 rotating in blocks which 35 are respectively slidable in the guides 36—37 and are supported by the screws 46; said screws can be turned in the nuts which are mounted on the respective supports 43 and 44 and thus regulate the vertical position of the shafts 45. The chain 40 47 is placed upon the wheels 48 which are mounted at one end of the shafts 45 and upon the wheel 49 which is disposed upon an intermediate shaft 50 mounted in a bearing 51 secured to the base plate 1.

45 Upon the shaft 50 is mounted a chain wheel 52 which is connected by a chain 53 with a like wheel 54 mounted on the shaft 5. This arrangement provides for the control of the rollers 32 and 33 in a synchronous manner both in mutual 50 relation and also in relation to the shaft 5. The diameters of the chain wheel are chosen in accordance with the speed of rotation which is to be given to the shafts 45, i. e. according to the number of turns which the said mandrel is to make between two successive rising movements of a given pasting roller.

Upon the support 43 is also mounted the movable bearing 6 above mentioned, which comprises the semi-circular bearing 55 mounted upon an 60 arm 56 pivoted at 57 to a horizontal support 58 secured to the support 43. The arm 56 carries a projection 59 which may be inserted under the hook 60 which is pivoted at 61 to the support 58 and is brought into the vertical position by the spring 62. A hand-controlled rod 63 is pivoted at 64 to the arm 56, and its end rests upon the hook 61; the spring 65 holds the same in the vertical position.

70 Below the said mandrel, and in the vertical plane passing through its axis, is disposed a jointed parallelogram whose extended small sides 66 are each terminated by two divergent branches carrying the rollers 67. One of the long sides 68a of the said parallelogram is rigidly secured to the

base plate 1; the other side, which is extended, serves as a controlling bar 68b. In this manner the rollers 67 may be brought into contact with the mandrel 8 which they support when the bearing 6 is removed; a suitable known device (not shown) holds the said parallelogram in the proper position.

The two uprights 68 mounted on the plate 1 comprise at the upper part two guides 69 in which are rotatably mounted the two rollers 70 and 71 between which is circulated the paper or like material to be wound. Upon the shaft of the lower roller 70 is mounted a hand wheel for the hand control of the device. The two arms 72 mounted on the brackets 68 carry an independent 15 roller 73 which serves as a guide for the said sheet to be wound; this sheet proceeds between two closely-spaced strips 74 which are suitably secured to the brackets 68 and also serve for supporting and guiding purposes when the paper is 20 cut off by the knife when the tube is finished.

Upon the legs 2 are mounted the supports 75 in which is rotatable the roll of paper or like material employed. Upon the said roller is applied a shoe 76 of india rubber, fibre or the like; 25 the said shoe is mounted on an arm 77 pivoted to an axle 78 secured to the main frame of the machine.

A spring 79 is attached at one end to the arm 77 and at the other end to a sliding member 80 30 movable in a guide 81 which is secured to the main frame and constantly presses the shoe 76 upon the said roller. The sliding member 80 is axially movable together with a shaft 82 which comprises a threaded part turning in a stationary nut 83; 35 upon the end of said shaft is mounted a hand wheel or crank 84 at the front of the machine.

On the same side of the machine as the movable bearing 6 is disposed perpendicularly to the axis of the machine a vertical frame 85, one of 40 whose vertical uprights 86 is situated in the middle vertical plane of the mandrel 8. Upon the said upright is pivotally mounted the frame 87, in each of whose cross-pieces 88 is formed a longitudinal slot 89 adapted for the insertion of the 45 rounded edge of one of the bars 90. The said bars are connected with the frame 85 by the pivoted levers 91 in such manner that they are displaced while remaining parallel. At the ends of the said bars are pivotally mounted the two 50 operating levers 92—93; the lever 92 carries a stud 94 slidable in a long guide 95 formed in the other lever 93. In the axis of the movable frame 87 is disposed a round rod 96 on whose end is mounted a hand wheel or crank 97, said rod being rotatable in supports secured to the uprights 98. The two cross-pieces 99 are rotatable together with the rod 96, and carry at their ends the two oppositely-situated rollers 100.

60 The operation is as follows:

The roll consisting of the raw material such as the paper, is placed upon the supports 75. The sheet F is drawn forward and is placed upon the roller 73 and between the rollers 70 and 71, as well as between the two blades of the guide 74; 65 the edge of the paper is inserted through the longitudinal slot in the mandrel 8, and if necessary the paper is drawn out by turning the roller 70 by means of the hand wheel provided for the 70 purpose.

By turning the handle 15, the operator causes the said edge to be seized between the shutter 11 and the stationary part of the said mandrel 8. The machine is now ready to operate. The 75

power being transmitted in any suitable manner to the pulley 16, the machine is coupled by releasing the fork 22, which is drawn back by the spring 25 and slides the sleeve 17 upon the shaft 5, and said sleeve thus engages the pulley 16. The mandrel 8 now begins to rotate, and the sheet F of paper is wound thereon. The rotation is communicated to the shafts 45 carrying the cams 40, by means of the chain 53 10 acting with the wheels 48 and 49. The said cams 40 will raise at the proper time the pasting rollers 32 and 33 which are immersed in the paste bath 41.

By means of the screws 46, the vertical position of the shaft 45 is regulated in such manner that the said pasting rollers will make a slight contact with the sheet of paper wound on the mandrel when they are in the upper position.

20 In the present example, the cam corresponding to the pasting roller 32 will raise this roller shortly before the mandrel 8 has made half a revolution, whilst the cam corresponding to the pasting roller 33 is displaced by $\frac{3}{4}$ of a revolution with reference to the preceding cam, and it raises the roller 33 shortly after the mandrel 8 has made three complete revolutions, the speeds of the cams and of the said mandrel having a ratio of 1 to 4.

30 The outline of the said cams forms an acute angle, so that the contact between the said pasting rollers and the sheet of paper will last for a very short time, and the rollers will leave upon the sheet only a narrow band of paste. Obviously, the said cam may have a very different outline, and may provide for a contact between the pasting rollers and the sheet of paper which corresponds to any desired fraction of a revolution of the said mandrel.

40 When the said mandrel has completed its fourth revolution, the cam 27 will have made a complete revolution, since the diameter of the wheel 31 is four times that of the driving wheel 30. The boss mounted on the said cam makes contact with the roller 26 and turns the fork 22 which actuates the sleeve 17. This latter brings the braking cone 18 into contact with the stationary cone 19, and in this manner the whole machine is instantly stopped. The fastening device 22^a allows the fork 22 to be held in the released position. The operator cuts off the sheet by holding his knife against the guide 74. The handle 15 is turned so as to allow the shutter 11 to drop in the interior, thus releasing the inner edge of the resulting paper tube.

To remove the said tube, the controlling bar 68^b is pushed out, and this brings the rollers 67 into contact with the mandrel 8. A suitable fastening device allows them to be held in this position in order to support the said mandrel. The bearing 6 is turned by pushing upon the rod 63 which pivots the hook 61 to the rear. The arm 56 is now no longer held, and it swings downwardly by its own weight, whilst the spring 62 brings the hook 61 to the vertical position. The paper tube can now be slid freely on the mandrel 8 and thus removed from the machine. The arm 56 is raised and the projection 59 is again placed under the hook 61. The mandrel being again supported by the bearing 6, the operator draws upon the bar 68^b, thus separating the roller 67 from the mandrel 8, and the machine is ready for the next operation.

When it is desired to manufacture tubes of the bellows type, the movable frame 87 is brought

into line with the axis of the mandrel by turning the said frame upon the upright 86. The operator directly slides the tube of the mandrel upon this frame which he then brings into the plane of the stationary frame 85. By means of the handle 97 he turns the frame consisting of the rollers 100 and the cross-pieces 99, so that the said rollers will make contact with the wall of the sack which they stretch symmetrically with reference to the plane of the frame 87. By 10 actuating the lever 93, the bars 90 are inserted at the same time into the corresponding slots 89 of the cross-pieces 88, thus forming the desired bellows portion. The resulting tension on the wall of the sack will pivot the roller frame 15 and thus bring it into the vertical plane. The finished tube can thus be readily removed after having again brought the frame 85 out of the plane of the frame 87.

The functioning of the brake affording the 20 regular unwinding of the roll of paper will be readily understood. The spindle 82 serves to regulate the tension of the spring 79 by more or less separating the block 80, according to the diameter of the roll of paper.

Obviously, the invention is not limited to the construction herein described and represented, which is susceptible of various modifications without departing from the spirit of the invention.

Having now described my invention, what I claim as new and desire to secure by Letters Patent is:

1. A machine for the manufacture of tubes of paper and like flexible material comprising a rotatable drum, a portion of the wall of said drum being pivoted to the other portion of said wall, substantially about a generatrix of said drum, an internal shaft adapted to rotate as a whole with said drum, eccentric parts on said shaft for supporting the free edge of said pivoted wall portion, manually operable means for rotating said shaft with respect to said drum, power means for actuating said drum and means for spreading an adhesive substance upon the layers 45 of material being wound.

2. A machine for the manufacture of tubes of paper and like flexible material, comprising a rotatable winding member for winding a band of said material, bearing members for supporting both ends of said winding member, means for moving one of said bearing members away from said winding member, a deformable parallelogram structure, rolling members disposed at the upper ends of two side members of said parallelogram and engageable with said drum for supporting the latter, when said bearing member is moved away from said winding member, whereby the tube may be removed from said winding member, said parallelogram structure 60 having a stationary side member parallel with the axis of said drum, power means for actuating said winding member, means for temporarily fastening said band upon said winding member and means for spreading an adhesive substance upon the layers of material while being wound.

3. A machine for the manufacture of tubes of paper and like flexible material comprising a rotatable winding member for winding a band 70 of said material, power means for actuating said winding member, means for temporarily fastening said band upon said winding member, means for guiding the band of material prior to winding said band comprising guiding 75

members and loose rollers freely rotatable in said guiding members, and means for spreading an adhesive substance upon the layers of material while being wound, the adhesive substance being applied in narrow strips extending longitudinally of the completed bag tube and spaced apart.

4. A machine for the manufacture of tubes of paper and like flexible material comprising a rotatable winding member for winding a band of said material, power means for actuating said winding member, means for temporarily fastening said band upon said winding member, clutching means between said power means and said winding member, means for automatically bringing said clutching means to the unclutching position after a predetermined number of revolutions of said winding member and means for spreading an adhesive substance upon the layers of material while being wound.

5. In a machine as claimed in claim 4, the provision of automatic braking means for instantaneously stopping said winding member when said clutching means are brought to the unclutching position.

6. A machine for the manufacture of tubes of paper and like flexible material comprising a rotatable winding member for winding a band of said material, power means for actuating said winding member, means for temporarily fastening said band upon said winding member a gluing device comprising substantially vertical guiding means, a gluing roller loosely slideable and rotatable in said guiding means, a rotatable shaft under said roller, a cam member on said shaft and adapted to support said roller, means for actuating said shaft at the speed proportional to the speed of the winding member, and a container for the adhesive substance, said roller being adapted to dip into said container in an intermittent manner during the rotation of said shaft.

7. A process for the manufacture of tubes of paper and like flexible material which are adapted to the manufacture of bags, consisting in winding a continuous band of said material in several turns upon a mandrel and interposing only narrow strips of adhesive material between the layers and transversely thereof, namely to secure the outer end of the wound strip to the underlying convolution and the inner end of the wound strip to the overlying convolution, the major portions of the convolutions of the wound tube between the strips of adhesive being left unsecured.

8. A process for the manufacture of tubes of paper and like flexible material which are adapted to the manufacture of bags, consisting in unwinding a supply roller of said material in form of a continuous band, providing the band with spaced apart narrow longitudinal strips of adhesive material suitably located, winding said band in several turns upon a mandrel and severing the tube thus formed from the uninterrupted band near the completion of the winding, the major portions of the convolutions of the wound tube between said strips of adhesive being left unsecured.

9. A process for the manufacture of tubes of paper and like flexible material, which are adapted to the manufacture of bags, consisting in winding an uninterrupted band of said material in several turns upon a mandrel and providing said band with narrow longitudinal strips of adhesive material respectively located one across

the end of the first convolution, one across the end of the latter and the others spaced apart between said two extreme ones, the major portions of the convolutions between the strips of adhesive being left unsecured.

10. A machine for the manufacture of tubes of paper and like flexible material of the kind referred to, comprising in combination a rotatable winding member for winding a band of said material, power means for actuating said winding member, means for temporarily fastening said band upon said winding member and means for automatically and intermittently spreading an adhesive substance upon the layers of material, along longitudinal narrow strips in time relation with the winding of said band.

11. A machine for the manufacture of tubes of paper and like flexible material of the kind referred to, comprising in combination a rotatable winding member for winding a band of said material, power means for actuating said winding member, means for temporarily fastening said band upon said winding member, gluing means adapted to spread an adhesive substance upon the layers of material and means for causing temporarily contacts of said gluing means with said material, in time relation with the winding of said band, whereby said adhesive substance is spread along spaced apart narrow strips upon said band.

12. A machine for the manufacture of tubes of paper and like flexible material of the kind referred to, comprising in combination an indeformable cylindrical mandrel adapted to be rotated for winding a band of said material, said mandrel being provided with a narrow longitudinal shutter forming part of its peripheral wall and adapted to be moved within said mandrel and to come flush with the outer surface of the remaining portion of the wall, said shutter being pivoted to the remaining portion of the mandrel substantially about a generatrix of the same and its opposite edge adapted to engage the corresponding edge of said remaining portion, whereby the band of flexible material may be clamped therebetween, both edges being faced with an adherence increasing material, means for pressing said edges against each other and displacing the shutter within the mandrel, power means for actuating said rotatable mandrel and means for spreading an adhesive substance upon said band.

13. A machine for the manufacture of tubes of paper and like flexible material of the kind referred to, comprising in combination a winding member for winding a band of said material, power means for actuating said winding member, means for temporarily fastening said band upon said winding member, at least one movable gluing roller parallel with said winding member, means for automatically bringing said roller in rather instantaneous contact with said winding member in time relation with the winding of the band of material and means for supplying said gluing roller with an adhesive substance.

14. A machine for the manufacture of tubes of paper and like flexible material of the kind referred to, comprising in combination a rotatable winding member for winding a band of said material, power means for actuating said winding member, means for temporarily fastening said band upon said winding member, at least one movable gluing roller disposed underneath and parallel with the winding mandrel, means for guiding said roller, at least one cam adapted to

- engage said roller and to shift the same into almost instantaneous contact with said winding member, means for operatively connecting said cam with said power means, and means for sup-
plying said roller with an adhesive substance. 5
15. A machine for the manufacture of tubes of paper and like flexible material of the kind referred to, comprising in combination a rotatable winding member for winding a band of said material, power means for actuating said winding member, means for temporarily fastening said band upon said winding member, at least one vertically movable gluing roller disposed underneath and parallel with the winding member, means for vertically guiding said roller, at least one cam adapted to shift the same into almost instantaneous contact with said winding member, means for operatively connecting said cam with said power means and means for supplying said roller 10 with an adhesive substance. 15
16. A machine for the manufacture of tubes of paper and like flexible material of the kind referred to, comprising in combination a rotatable winding member for winding a band of said material, power means for actuating said winding member, means for temporarily fastening said band upon said winding member, at least one vertically movable gluing roller disposed underneath and parallel with the winding member, means for vertically guiding said roller, two cams engaging the ends of said roller, respectively, so as to permanently carry the same, the outline of said cams including at least one very acute salient part, whereby said roller may be shifted into almost instantaneous contact with said winding member, means for operatively connecting said cams with said power means and means for supplying said roller with an adhesive substance. 20
17. In a machine as claimed in claim 13, the provision of means allowing to adjust the distance between the axis of the winding member and the axis of the gluing roller when in its pasting position, whereby winding members of various diameters may be used. 25
- 45 18. In a machine as claimed in claim 14, the further feature residing in that said cam is rotatable and in the provision of means for adjusting the axis of rotation of said cam and the axis of the gluing roller toward and from the periphery of the winding member. 30
19. In a machine as claimed in claim 13, the provision of means for separately shifting each end of the gluing roller towards and away from the winding member to adjust it exactly parallel with said winding member. 35
20. A machine for the manufacture of tubes of paper and like flexible material of the kind referred to, comprising in combination a rotatable winding member for winding a band of said material, power means for actuating said winding member, means for temporarily fastening said band upon said winding member, at least one vertically movable gluing roller disposed underneath and parallel with the winding member, means for vertically guiding said roller, two rotatable cams adapted to engage both ends of said roller and having each an outline forming at least one very acute salient part so as to lift the gluing roller into almost instantaneous contact with said winding member, imperative gearing means for operatively connecting said rotatable cams with said power means, means for supplying said roller with an adhesive substance and means for separately adjusting the distance between the axis of rotation of each of said cams and the axis of the winding member. 40
21. A process for the manufacture of tubes of paper and like flexible material which are adapted to the manufacture of bags, consisting in unwinding a supply roller of said material in form of a continuous band, providing the band with spaced apart narrow, transverse strips of adhesive material suitably located and extending substantially the width of said band, winding said band in several turns upon the mandrel, and severing the tube thus formed from the uninterrupted band after several turns have been wound on the mandrel, the major portions of the plies between the strips of adhesive being left unsecured. 45

RENE JARRIER.
